MACHINE FOR AUTOMATICALLY PLAYING PIANOS AND SIMILAR INSTRUMENTS.

1,014,606.

Specification of Letters Patent.

Patented Jan. 9, 1912.

Application filed November 7, 1900. Serial No. 35,715.

To all whom it may concern:

Be it known that I, ALFRED WILLIAM NUNN, a subject of Victoria, Queen of Great Britain, now residing in Cambridge, in the county of Middlesex and State of Massachusetts, have invented a new and useful Improvement in Machines for Automatically Playing Pianos and Similar Musical Instruments, of which the following is a full, clear, and exact description, reference being had to the accompanying drawings, forming a part of this specification, in explaining its nature.

The invention relates to the herein described improvements in machines or devices for automatically playing pianos, organs and similar musical instruments.

The object of the invention is to provide a complete machine or apparatus which shall not only have a superior construction and desirable arrangement of its working parts with respect to each other and a ready accessibility to them or such of them as need most frequent inspection, adjustment or repair, but also means by which the machine or apparatus as a whole is made adjustable to the key-board of any piano without requiring any change or the removal of any part of the piano or of the machine, and this is true as to all pianos of the market, upright, grand and square.

Another object of the invention is to provide means for varying the expression or striking force of the strikers or fingers by changing at will the power applied to groups of fingers, preferably the bass and treble ranges.

Other features of my invention will be understood from the description below given and the claims.

I will now describe the invention in detail in connection with the drawings where—

Figure 1 is a view principally in front elevation, portions of the frame and casing of the machine being removed in places to illustrate parts behind the same. Fig. 2 is a view in rear elevation, parts of the frame and casing being removed to show portions of the machine in front of them. Fig. 3 is a vertical section upon the dotted line 3—3 of Fig. 1. Fig. 4 is a view in plan. Figs. 5 and 6 are detail views to represent portions of the music feed and rewinding devices.

Fig. 7 is a view in plan of the well of the bellows. Fig. 8 is a view in section and elevation of an improved take-up roll. Fig. 9 is a view in cross section upon the dotted line 9—9 of Fig. 8. Fig. 10 is an enlarged detail in section, showing the valves and their arrangement in their respective chambers. Fig. 11 is an enlarged perspective of one of the pneumatic motors. Fig. 12 an enlarged perspective of one of the strikers, a portion of its striking arm being broken away, and Fig. 13 a section showing the means of connection of the striker with its support. Fig. 14 is an enlarged horizontal section of the chamber *e* shown in Fig. 10, two of these chambers being shown side by side.

In a general way the machine follows the operation of the machines of the market upon which the invention is an improvement and which use pneumatic motors for operating the key strikers, a tracker-board and a perforated paper music strip or web for controlling the action of the motors.

Referring to the drawings:—*A* is the tracker-board. It is mounted at or near the upper corner of the main channel-board to extend diagonally forward from it. It has the usual wind channels or ways *a* extending through it to its lower end and the curved upper surface *a*¹ over which the operating paper strip or web *A*¹ is fed. The wind channels are connected with the primary valves by means of the rubber tubes or flexible pipes *a*² in the usual way. The operating paper web is carried by the roll *A*² mounted on suitable stands back of the tracker-board and in the usual way and it is drawn and taken up by the take-up spool *A*³ mounted in front of but below the tracker-board and below the upper surface *a*¹ of the channel-board. This arrangement of tracker-board, roll and take-up is a desirable one because it reduces the height of the machine. The take-up spool is operated in the usual way from the wind or other motor, the connection being by means of the gear *a*³ on the take-up spool shaft, pinion *a*⁴, the shaft *a*⁵, the sprocket wheel *a*⁶, sprocket chain *a*⁷, sprocket wheel *a*⁸ on a shaft *a*⁹ driven by the wind motor. This is the usual method of turning the take-up spool but any other equivalent mechanism may be used for operating it with this exception that the

pinion a^4 is loose on its shaft instead of being fixed to it and for the purpose of permitting the same shaft to be used in rewinding the paper upon the original roll in this manner: The shaft bears a sprocket wheel a^{10} , (see Fig. 5) which is loose upon it. Both it and the pinion a^4 have members of a clutch upon their opposing faces represented in this instance as provided by projecting pins. Between them on the shaft is a section a^{11} of a clutch movable lengthwise the shaft but keyed to the shaft to be turned by it. This clutch has two clutch faces a^{12} and a^{13} , one of which is adapted to engage the clutch of the pinion a^4 when moved into contact with it and the other to engage the clutch of the sprocket wheel a^{10} when moved into contact with it. The movement of the clutch into engagement with one moves it out of engagement with the other. When moved into engagement with the sprocket wheel the sprocket wheel is caused to revolve and to turn the sprocket chain which connects it with the sprocket wheel on the rewinding mechanism, (see Fig. 5). The take-up spool is of ordinary construction excepting that the end sections or sleeves, which are movable lengthwise the core for the purpose of adjustment to paper varying in width, are held in their adjusted positions upon the core by friction springs which are attached to the core, extend lengthwise the core in a recess therein and have their free ends bent inward into an inward extension of the recess. The spring is shaped to exert an upward pressure against the inner surface of the sleeve and thereby holds it from slipping on the core while it permits it to be readily moved upon the core in either direction and without releasing or operating any part. In the drawings a^{14} , a^{15} represent the sleeves, a^{16} the core, a^{17} , a^{18} the recesses in the core, a^{19} , a^{20} the friction springs contained in said recesses, the end a^{21} of each being fast to the core, the end a^{22} of each being free and the section a^{23} of each bearing against the inner surface of its respective sleeve with any desired stress.

Before describing the valve action I will describe the general arrangement of the channel-boards and primary and secondary valves, fingers, finger supports and the pneumatic motors with respect to each other.

B is the main channel-board. This is vertically arranged near the front of the machine in front of the vertical arms of the strikers, below the upper level of the strikers and above the primary and secondary valve chambers. The channel-board may be said to be in two parts or sections, viz: the vertical part which I have lettered B^1 and the horizontal part which I have lettered B^2 and which extends horizontally from near the top of the vertical part. These sections of the channel-board inclose on the

front and top a space or chamber B^3 in which are arranged the pneumatic motors for operating the key strikers or fingers, the top section of said channel board being removable in order that the motors and fingers may be easily accessible in case of needful repair. The strikers have a right angular shape, one arm horizontally extending backward from their pivotal point and the other arm extending downward from the pivotal point back of the pneumatic motors. 70

In the drawings C represents the angular strikers or fingers, c the horizontal, backward extending arms having the striker ends or projections c^1 upon their under surfaces; c^2 is the downward vertical arm of each striker. Each striker is independently pivoted to an individual support C^1 which is detachably secured to the section B^2 of the channel-board by a screw c^3 . A portion of 80 each support bears on the top of the channel-board section B^2 and a portion forms a shoulder c^4 which bears against the back edge of the channel-board and each support is slotted to provide a recess for receiving 85 the finger and a supporting arm upon each side thereof, (see Figs. 12 and 13). Each striker and its support are together independently removable from the channel-board by simply unscrewing the fastening 90 screw c^3 . They are so shaped, arranged and mounted upon the upper surface of the channel-board as to be accessible without the removal of any part of the machine. 95

D represents the pneumatic motors, E the 100 line of primary valve chambers, valves and diaphragms and F the line of secondary valve chambers and valves.

Fig. 3 well shows the arrangement and relation of both sections of the channel-board, the strikers, the pneumatic motors, the primary valves and the secondary valves with respect to each other, the top of the machine, its back, its front and the reservoirs, and clearly represents their compact 105 compass and relation to each other and accessibility.

The pneumatic motors D are attached to the machine in the following way: The front line is attached to the back side of the vertical section B^1 of the channel-board and the second and third lines are attached to the faces of longitudinal crossbars depending from the horizontal section B^2 of the channel-board. They preferably are arranged to hang downward, that is, their hinged ends are uppermost, and they are also preferably arranged in lines of three from front to back. By suspending them or hanging them down there is less liability 120 of any particles of foreign substances interfering with their action. This arrangement also provides for the better application of power to the strikers and also provides a compact organization. The motors 125 130

also differ from ordinary motors in that they are smaller and yet have the same compass or capacity and power. This result is obtained because the two sides of each motor are connected at their hinged end by a soft leather or flexible hinge which is attached to the inner surfaces of the sides and the whole is then covered by a leather or flexible covering, (see Fig. 11). This provides a construction in which no part of the leather covering is between the sides of the motor at any time and the sides can therefore be closed completely together and the entire capacity of the motor can be employed.

I have represented in Fig. 11 the construction in detail of one of the motors where d^1 represents one side of the motor, d^2 the other, d^3 the inner, flexible hinge and d^4 the outer inclosing envelop. d^5 is the depending bar to which the second line of motors is secured; d^6 is the depending bar to which the third line of motors is secured. Each motor is connected with a depending arm of the striker by a pull rod d^7 attached at one end to the moving side of the motor and at its other end to the lower end of the finger, (see Fig. 3). There are three different lengths of rods, the front motors requiring, of course, longer rods, the second line rods of intermediate length and the back line the shortest lengths. The exhaustion of air from the motors actuates the fingers by causing the sides of the motors to be moved to the fixed sides and thereby pulling the depending arms of the strikers forward. The return of air to the motors causes the movable sides to assume their original position and thereby to move the fingers to their original position. To assist in this return action a light spring d^8 is employed to bear against the movable side to open it. This construction is represented in Fig. 11. I prefer that each connecting rod d^7 be secured to the lower end of the finger arm in a manner to permit it to be slipped downward and disengaged from the arm without removing the adjusting or stop nuts on the rods. It will be understood that the back end of each rod is threaded and carries two nuts, (see Fig. 3) one of which bears against the front face of the finger arm and the other against the back face thereof. The front end of each rod is secured to the motor in the same way. To permit this downward removal of the rod from the finger arm, the finger arm is provided with a slot c^6 (see Fig. 12) in its lower end opening downward. Each slot c^6 is made slightly less in width than the diameter of the connecting rod d^7 , a circular enlargement q^7 being provided in the slot to give the rods d^7 a slight transverse play. By this construction the rods d^7 may be readily inserted and removed from the

fingers c^2 , and the analogous construction on the motors without removing the nuts by springing the ends of the fingers slightly so as to widen the slot c^6 and release the connecting rod from the circular enlargement, the rod, of course, being of proper diameter to slide easily out from the slot. The fingers are moved backward against the stop rail c^5 which keeps the fingers in line and at a proper height with regard to the keys of the piano.

I will now describe the primary valves, valve chambers and diaphragms and manner of their operation:—

e^1 represents the diaphragm chamber with which each wind-way of the tracker-board is freely and at all times connected by a passage in the connecting tube (see Figs. 3 and 10).

e^2 is a flexible diaphragm in the diaphragm chamber; the diaphragm chamber is oblong in shape, being wider from front to back than from side to side and the diaphragm is of corresponding shape. It is attached to the upper end of the valve spindle e^3 which carries the valves e^4 , e^5 controlling respectively the ports e^6 and e^7 of the channel e^8 . The chambers, f^3 and E^1 , are vacuum chambers, each being connected with the exhaust mechanism below described.

The operation of the valve so far is this:—When a wind-passage a of the tracker-board is open the ingoing atmosphere presses the diaphragm e downward causing the upper valve to close the port e^6 between it and the channel e^8 and to open the port e^7 between the channel e^8 and the outer air and at the same time to slightly compress the spring e^8 , (see Fig. 10). This restores atmospheric pressure in the channel e^8 , which raises the diaphragm f of the secondary valve f^1 thereby causing the said valve to be moved upward to open the port f^2 between the secondary air chamber f^3 and the channel f^4 leading to the pneumatic motor and closing the port f^5 to the outer air thereby putting the pneumatic motor in communication with the vacuum chamber f^3 through the said channel and the connections from said channel with the motor, the said channel connecting at points f^6 with the front line of motors and at points f^7 with the second line of motors and at points f^8 with the third line of motors. When, however, a wind-way of the tracker-board is closed by the paper air is exhausted from the tracker-board side of the diaphragm by means of a small pass or hole e^9 between the primary air chamber E^1 and the diaphragm chamber. This equalizes the pressure upon both sides of the diaphragm e and permits the spring e^8 to move the diaphragm and valve rods and valves upward to close the lower port e^6 of the channel e^8 to the outer air and to open the port e^5 between said

channel and the primary air chamber. The closing of the port e^6 of the channel e^7 to the outer air and the opening of the connection of channel e^7 with the primary air chamber 5 E lowers or equalizes the pressure in said channel with that of E^1 so that the diaphragm, f , moves downward and secondary valve f^1 with it and closes the port between the secondary air chamber f^3 and the main channel 10 10 by which the air has been drawn from the pneumatic motors and opens the ports connecting the main channel with the outer air thereby equalizing the pressure in the main channel with the outer air and permitting 15 the pneumatic motors to fill and open.

The primary air chamber E^1 is connected with the main reservoir G by means of the conducting passages g , in the pipes g^1 , one at each end of the air chamber and which 20 extend to a vertical conductor opening at its lower end by a horizontal passage into the main reservoir. The secondary air chamber f^3 is connected with both the main reservoir G and the reservoir G^1 as follows:— 25 with the main reservoir G by means of the channel H (see Fig. 2); the openings between this channel and the air chamber f^3 are controlled by means of two slide valves H^1, H^2 . One of the openings connects with 30 the portion of the apparatus which operates the treble range of fingers only and the other with the portion of the apparatus which operates the bass fingers only.

It should be understood that the secondary air chamber is in two parts, being separated by a partition X at or near the center of its length or upon a line to correspond with the line of division between the treble register and the bass register. By moving 40 the valve H^1 that portion of the secondary air chamber which connects with the motors operating the treble register is connected with the main reservoir G ; by moving the slide H^2 that portion of the secondary air 45 chamber which connects with the motors which operate the bass register of fingers is connected with the main reservoir. Both passages may be opened at the same time connecting the main reservoir to all the 50 motors and both passages may be closed. The extent of the vacuum will vary, of course, according to the extent of movement of the slide and the consequent variations in the areas of the ports. It is more perfect, of course, when the passages are wide open.

The reservoir G^1 in which the vacuum is lighter is connected by means of the passage g^2 with a chamber g^3 which opens into the secondary air chamber. This chamber 60 g^3 is arranged to span the line of division between the two sections of the secondary air chamber and connect with both by means of two holes g^4 , one for each section, one of which holes as shown in Fig. 3. Each 65 of these holes has a check valve g^5 which is

operated by variations in pressure so that when stronger vacuum is employed upon one side of the secondary air chamber the valve is closed and the pressure cannot extend through said holes and chamber to the other side. The reservoir G^2 is connected by means of a conductor g^6 with the wind motor G^3 which operates the wind engine for operating the paper or other music-feeding apparatus. The usual type of wind motor and wind engine may be used. The reservoirs, however, have important improvements and also the bellows which operate them.

Each of the three reservoirs G, G^1, G^2 has a fixed, flat, stationary base J of the full size of the reservoir. It also has a movable flat top j which is adapted to be moved toward and from the base J . It is provided with flexible, air tight sides j^1 and with 80 passages j^2 through the base J by means of which the chamber of each reservoir is exhausted of air by the exhaust bellows K, K^1 . As there are three reservoirs represented there are shown three sets of passages j^2 in 85 the base J , (see Fig. 7). It will be understood that one set communicates with the reservoir G , the second with the reservoir G^1 and the third with the reservoir G^2 . The base J forms the top of an air chamber 90 J^1 which is common to all the reservoirs. The reservoir G is connected with the passage H by means of the passages j^3 extending through the base J and the horizontal passage j^4 in the air chamber J^1 , the said 95 passage j^4 being contained in the air chamber J^1 but not being connected with it so that the reservoir G reaches the passage H by means of passages j^3, j^4 . The reservoir G^1 is connected with the passage g^2 , (see 100 Fig. 1) by means of the passages j^5 in the base J and the passage j^6 contained in the air chamber J^1 , (see Fig. 7). By making the reservoirs of the shape and construction described their capacity is doubled, that is, 105 as compared with the ordinary type of reservoir which is hinged at one side. This is due to the fact that the entire movable side or top moves the same distance with regard to the base so that all portions of the reservoir within it are of equal capacity. This permits the reservoirs to be arranged horizontally near the base of the apparatus and to thus economize space and is one of the means by which it becomes possible to obtain 110 the compact arrangement of motors, channels and strikers above described.

It will be understood that in operation air is drawn from the reservoirs by the bellows and that the reservoirs act to operate the 115 motors by drawing air from the connecting channels and that this action of the reservoirs is obtained by the use of springs which are compressed by the bellows and which act to distend the reservoirs and 120

130

cause them to suck or draw air from the channels. The reservoir G owes its power to the fact that its springs are heavier than those used in the light reservoirs. Any type of spring for accomplishing this purpose may be used and I have represented in Fig. 1 the spring J² which is a common form of spring only more powerful than is usually employed for this purpose. In order that the reservoirs G¹, G² may be shut off from the effect of the heavy pressure caused in exhausting the heavy reservoir I have provided all the movable tops *j* of the reservoirs G¹, G² with the valve J³ upon their under surface and which valve is adapted to be moved against the base J and close the outlets or passages *j*² so that when the said reservoirs G¹, G² are in action their tops are drawn down to the base, their passages *j*² are closed and there is no connection between their chambers with the high pressure reservoir G. If these valves were not used there would be no difference in the pressure of the three reservoirs. I have embodied the same principle of construction in the bellows and for the same reasons, to increase their capacity without increasing their area and to economize space.

The top *k* of each bellows is the bottom board of the air chamber J¹; *k*¹ is the movable bottom of each bellows and *k*² is the flexible side and end walls. Vertical movement is given to each bottom by means of the pedals *k*³, one for each bellows, pivoted at *k*⁴ to the base of the machine and bearing against an anti-friction roll *k*⁵ at the outer end of a rock-lever *k*⁶ which is pivoted at *k*⁷. Each rock-lever is connected with the movable bottom of the bellows by a connecting rod *k*⁸, (see Fig. 3). A spring *k*⁹ acting through the lever *k*¹⁰ pivoted at *k*¹¹ and operating against the rock-lever serves to return the bottom to its highest or normal position as well as to return the pedals. The operation of this part of the machine is as follows: The operator by his feet works the pedals *k*³, *k*⁸ up and down and causes the air to be exhausted from the reservoirs, the reservoirs G¹, G² to be practically closed and the passages connecting them with the bellows shut as above explained. This provides the machine with two powers, viz: the heavy and the light power, one of which is constantly acting and the other of which acts as it is required by the use of the controlling valve, it being understood that the power is by these valves graduated from a power approximating the light and from heavy to light as may be desired. Of course the bellows are connected with the air chamber J¹ in the usual way.

I have provided the machine with means for vertical adjustment. This is accomplished by means of the threaded spindles *m* upon the lower ends of which are mounted

the caster rolls M. They are attached to each corner of the frame of the machine by brackets *m*¹ and *m*². The bracket *m*² holds a worm-nut *m*³ having an interior thread through which the threaded spindle *m* extends. The worm-nut is turned by a worm *m*⁴ which engages the worm and is adapted to be turned from outside the case by a wrench. I prefer to couple the two spindles at each end together by the common worm-shaft *m*⁵ operating two worms, one for each spindle.

In Fig. 1 the levers N operate the rewinding mechanism, the lever N¹ controls the time of the music-feeding engine, the levers N², N³ control the bass and treble expression, the lever N⁴ controls the operation of the loud pedal of the piano. These levers and connections, excepting, of course, the expression levers, are of the ordinary type and are connected in the ordinary way.

The by-pass connecting the diaphragm chamber with the air chamber E¹ is shown in Fig. 10, but is not shown in Fig. 3 because the passage is so small.

It will be seen that by the arrangement of the fingers or strikers, their wind-motors and the air-exhausting devices with relation to each other an unobstructed space below the strikers is obtained of such extent and size that the machine is adapted to be moved into operative relation with the keys of any piano without requiring that any part of the piano be removed or cut away to permit this to be accomplished. This is due to the peculiar arrangement of the operative parts of the machine with respect to each other.

In Fig. 3 I have shown means for adjusting the position both vertically and horizontally of the connecting device which actuates the pedal of the piano.

Having thus fully described my invention, I claim and desire to secure by Letters Patent of the United States:—

1. In a machine for playing pianos and other musical instruments, the key-strikers having arms angularly arranged with respect to each other and pivoted at or near their point of divergence in a manner to cause the striking arms to extend backward horizontally and the power-receiving arms to extend downward vertically, in combination with a series of pneumatic motors, one for each key striker, each located in front of its striker with its movable side toward the vertical arm of said striker, and a rod connecting each motor with its striker, and means for operating said motor, whereby each motor will pull its striker to cause its action upon the piano key, as described.

2. In a machine for playing pianos and the like, the combination of a channel board having a horizontal portion, a series of pneumatic motors supported from the under side of the horizontal portion of said chan-

nel board, a series of strikers having arms angularly arranged with respect to each other, each striker being separately pivotally mounted upon the rear edge of said channel board, its horizontal striking arm extending rearward and its vertical arms extending downward substantially parallel with said pneumatic motors, a rod connecting each motor with its striker, and means whereby each motor is operated as described.

3. In a machine for playing pianos or the like, the combination with a tracker board and paper rolls, of a supporting rail located in rear of said tracker board and paper rolls, a series of independent striker supporters, one for each striker mounted on the upper rearward surface of said rail, each having an exposed movable fastener for attaching one of said strikers thereto, and an exposed movable fastener for attaching said supporter to said rail, whereby each separate striker may be reached and removed without removing either of the others and without interfering with said tracker board and paper rolls, as described.

4. In a machine for playing pianos and other musical instruments, in combination with a tracker board and paper rolls, a supporting rail located in rear of said tracker board and paper rolls, a series of striker supports each having two projecting portions between which and to which a striker may be pivoted, a striker pivoted to each support, and a series of pneumatic motors located in front of said strikers, and means connecting said strikers to said motors whereby the action of each motor upon said striker will cause said striker to strike the piano key, as described.

5. In a machine for playing pianos and other musical instruments, a channel board, and a series of striker supports each having a seat to rest upon the upper surface of said channel board, and a shoulder to bear against an edge of said channel board, and means for attaching said support to said channel board whereby said support is held against said channel board and prevented from moving laterally thereon, in combination with a series of strikers each striker being supported in its support, and means whereby each striker is operated, and a tracker board and its paper rolls, said tracker board and paper rolls being located in front of the rear edge of said channel board, whereby each striker may be reached without disturbing said tracker board and rolls, as described.

6. In a machine for playing pianos and the like, the combination of a rail, a striker support having a seat and shoulder for fitting said rail and mounted thereon, means for attaching it to said rail, said seat and shoulder preventing said support from mov-

ing about a center, said support having arms forming a recess to receive a portion of the striker and extending downward below the level of said rail, and a striker pivoted to said arms below the level of said rail whereby the upper edge of the striking end of said striker is brought onto substantially a horizontal level with the upper edge of said rail, as and for the purposes described.

7. In a machine for playing pianos and the like, the combination of a channel board having a horizontal portion, a tracker board projecting diagonally from the front edge thereof, two paper rolls, one located on each side of said tracker board, the upper paper roll being mounted upon the horizontal portion of said channel board and in front of its rear edge, and a series of strikers mounted on the rear edge of said channel board, said tracker board, said upper music roll, said channel board and said line of strikers forming the upper portion of said machine whereby the line of strikers is exposed, easy of access for repairs and the like, as and for the purposes set forth.

8. In a machine for playing pianos and other musical instruments, the combination of a channel-board or rail at the top of the machine, a line of horizontal striker supports attached to the upper surface of the channel-board or rail and extending backward horizontally therefrom, each of which supports is made accessible without the removal of any fixed covering device, and a line of strikers pivoted to said supports.

9. In a machine for playing pianos and the like, the combination of a channel board having a horizontal portion and a vertical portion arranged to form a motor-holding chamber in front of the strikers, the motors contained in said chambers and strikers arranged in rear of said motors and connecting devices connecting said strikers with said motors, whereby the movement of each motor will be communicated in a horizontal line with its striker to cause the striking end of said striker to make a vertical movement, as set forth.

10. In a machine for playing pianos and the like, the combination of channel boards arranged in angular relation to each other to form a motor-holding chamber in front of the strikers, a series of strikers pivotally mounted upon the rear edge of the horizontal portion of said channel board, a series of motors located parallel with the vertical portion of said channel board and suspended from the horizontal portion of said channel board, and between the vertical portion thereof and the strikers, and means whereby the movement of each motor will be communicated in a horizontal line with its striker, as described.

11. In a machine for playing pianos and other musical instruments, the combination

of channel-boards arranged in an angular relation to each other to form a motor-holding chamber, a series of motors contained in said chamber, and a series of strikers located in rear of said motors, a series of horizontal pull rods each connecting a motor with one of said strikers, whereby a movement of the rear face of each motor will give a forward actuating movement to its striker, as and for the purposes described.

12. In a machine for playing pianos and the like, in combination, a support, a line of strikers mounted on said support, a series of motors arranged in parallel lines and suspended from the under side of said support, each motor being connected with one of said strikers, and a channel board having a vertical portion located in front of said motors and means for pneumatically connecting said channel board with said motors, as described.

13. In a machine for playing pianos and other musical instruments, the combination of a channel-board vertically arranged near the upper part of the machine, a channel-board extending backward horizontally from the inner side of the vertical channel-board at or near its top, strikers carried by said last-named or horizontal channel-board, rails below said last-named or horizontal channel-board carrying motors, motors carried upon the back side of said first-named or vertical channel-board, the strikers and connections between the motors and the strikers.

14. In a machine for playing pianos and other musical instruments, the combination of channel-boards disposed in the upper part of the machine to form a motor-holding chamber open at its back and in line with the strikers, the strikers, motors contained in said chamber with their hinged ends uppermost and means connecting the lower ends of their movable sides with the strikers.

15. In a machine for playing pianos and other musical instruments, the combination of an angular striker, a support for the same disposed to hold the striker with one arm extending backward horizontally and one arm extending downward vertically and a motor in front of the vertical arm having its hinged end uppermost and means connecting its movable side with the vertical arm of the striker.

16. In a machine for playing pianos and other musical instruments, the combination of a striker, a support for the same disposed to hold the striker with an arm extending backward horizontally, and a motor having its hinged end uppermost, and means connecting its movable side with said striker, as set forth.

17. In a machine for playing pianos and the like, in combination with a tracker board and paper rolls, a rail located in rear of

said tracker board and paper rolls, a series of striker supports located on the upper side thereof, a series of strikers each pivotally mounted in one of said supports, and having an operating arm depending therefrom, a series of pneumatic motors located in front of the operating arms of said strikers each having a depending arm in line with the operating arm of one of said strikers, the operating arm of each striker being slotted at its lower end, a rod connecting the operating arm of each striker with its motor, a pair of clamping nuts located on said rod, one on each side of said operating arm adapted to clamp said rod to said operating arm whereby the loosening of the means of connection between any of said striker arms and said rail and of one or both of its clamping nuts will enable said striker to be removed from said machine without interfering with said tracker board, said rolls, or said motors, as described.

18. In a machine for playing pianos and the like, the combination of a pivoted striker having a vertical operating arm, a motor located in front of said striker hinged at one end, said hinged end being in substantially the same horizontal plane with the pivot of said striker, its movable side being provided with an arm projecting from its lower edge having a longitudinal slot of substantially equal width throughout its length and having a circular enlargement between its ends, in combination with an operating rod having a diameter slightly greater than the width of said slot passing through said slot and having upon it a pair of clamping nuts one located on each side of said arm and adapted to bind said rod thereto, the other end of said rod being connected to the operating arm of said striker, and means for operating said motor, as and for the purposes described.

19. In a machine for playing pianos and the like, the combination of a rail, lines of pneumatic motors, means for supporting said motors from their upper ends, said means lying in substantially the same plane with said rail, a series of strikers pivotally mounted on said rail, and connections between the motors and strikers, each motor having a hinged side, the axis of the hinge of each motor and the pivot of each striker lying parallel to each other and in substantially the same horizontal plane, as set forth.

20. In a machine for playing pianos and other musical instruments, the combination of pneumatic motors vertically arranged in lines with their hinged ends uppermost and in front of the strikers with the strikers having vertical arms parallel with the motors and horizontal connections connecting the lower ends of the arms with the lower end of the motors.

21. In a machine for playing pianos and other musical instruments, the combination of channel-boards, the lines of pneumatic motors vertically arranged with their hinged ends uppermost upon one side of one of the channel-boards and below the other, strikers back of said lines of pneumatic motors connected with the motors and channels or passages connecting the channel-boards with 10 the motors.
22. In a machine for playing pianos and other musical instruments, the combination of the channel-boards disposed in the upper part of the machine to form a motor-holding chamber open at its back, a series of motors contained in said chamber, a tracker board and the rolls of music, holding and feeding mechanism, said tracker board extending in a diagonal direction from one of the upper corners of said channel-board, and one of said rolls being located below said tracker board, and the other horizontally in line with it, as and for the purposes described.
23. In a machine for playing pianos and the like, a combination of the tracker board, pneumatic motors, exhausting devices, a series of diaphragm chambers connected with said tracker board, a primary air chamber located thereunder, a series of primary diaphragms each separating said primary air chamber from one of said diaphragm chambers, a secondary air chamber located on the same level with said primary air chamber and the rear thereof, a series of channels located below said primary and secondary air chambers and connected to said primary air chamber, a series of secondary diaphragms each separating one of said channels from said secondary air chamber, and a series of 30 motor channels connecting said secondary air chamber with said motors, a series of primary valve structures each carried by one of said primary diaphragms and comprising a valve closing an opening between 35 said primary air chamber and one of said first named channels and a second valve closing an opening between said first named channel and the atmosphere, and a series of secondary valve structures each carried by 40 one of said secondary diaphragms and comprising a valve located above it closing an opening between said secondary air chamber and a motor channel and a second valve closing an opening between said motor channel and the atmosphere all arranged together and operating as described.
24. In a machine for playing pianos and other musical instruments, the combination of the strikers having striking arms extending backward horizontally, and operating arms extending downward vertically, a channel-board, said strikers being pivoted thereto at the junction of said striker and operating arms, pneumatic motors supported from the underside of said channel-board 45 and in front of said operating arms, and connections between said motors and said operating arms, whereby the strikers are caused to have striking impulses by a drawing action upon said operating arms, and are lifted by a pushing movement against said arms.
25. In a machine for playing pianos and the like, a channel board having a horizontal section and a vertical section, a series of strikers mounted on the rear edge of said 50 horizontal section and having a horizontal striker arm extending rearward, a vertical power arm extending downward, a series of pneumatic motors hanging from the underside of said horizontal section of said channel board in front of the line of strikers, each placed with its movable side toward the line of strikers, a series of connecting rods each connecting the movable side of one of said motors with its striker, and a 55 stop rail located in rear of the lower ends of said strikers, whereby each movement of each motor will be communicated to its striker, and said stop will serve not only to limit the rearward movement of the power arm of the striker, but also the opening movement of the motor, as set forth.
26. In a machine for playing pianos and other musical instruments, the combination of the channel-boards arranged in two sections, one horizontal, the other vertical, said sections being connected with each other, a series of strikers pivotally connected to the upper rear edge of the horizontal section of said channel-board, pneumatic motors arranged below said horizontal section of said channel board and between its vertical section and said strikers, connections between said pneumatic motors and said strikers, and pneumatic means for operating said motors, 60 as and for the purposes described.
27. In a machine for playing pianos and the like, the combination of a primary and secondary air-chamber located side by side, said secondary air-chamber being provided with a series of openings closed by diaphragms adapted to operate valves connected therewith, said openings each leading to a channel connecting said secondary air-chamber with said primary air-chamber, a series of diaphragm chambers, a series of diaphragms separating said diaphragm chambers from said primary air-chamber, a series of openings each leading from said primary air-chamber to said channel and controlled by a valve connected with one of said diaphragms, two sets of channels, one leading from said secondary air-chamber to feed the motors, the other leading to the tracker board, a series of motors located in 70 rear of said channels, a channel board, a series of strikers mounted upon the rear side of the upper portion of said channel board, and a tracker board mounted upon the front side of said channel board, all as described.

28. In a machine for playing pianos and other musical instruments, the combination of a base having an air chamber which is connected with the air chambers of the machine by passages, two air-exhausting reservoirs connected with the chamber in the base and by separate passages with the said air chambers of the machine, air-exhausting devices for operating both exhausting reservoirs and a valve carried by one of the exhausting reservoirs adapted to close a channel connecting it with the other exhausting reservoir when the pressure thereon exceeds its own limit.
29. In a machine for playing pianos and other musical instruments, the combination of the strikers, their operating motors arranged back of the strikers, the channel-boards arranged above and in front of the motors, the air chambers and passages arranged below the motors and channel-boards but above the exhausting devices and the said exhausting devices.
30. In a machine for playing pianos and other musical instruments, the combination of the fingers or strikers, their pneumatic motors arranged in front of them, the channel-boards arranged over the strikers and in front of them, the air channels, passages and valves arranged immediately below them, the said operative parts of the device being contained in the upper portion of the machine, one or more air reservoirs and one or more exhausting bellows, one arranged over the other and each having sides or ends which are movable uniformly throughout their extent from their base or support.
31. In a machine for playing pianos and other musical instruments, the combination of the air-exhausting bellows, its movable side, all the parts of which are uniformly movable with respect to its base and means for moving the side comprising a lever, a link connecting the lever with the movable side and a pedal, the upper end of which is supported with a moving contact by said link, its lower end being hinged to the base of the machine, whereby the lower the pedal is depressed the nearer said link is brought to the hinge of said pedal, as described.
32. In a machine for playing pianos and other musical instruments, the combination of the fingers or strikers, the pneumatic motors arranged in front of the fingers or strikers, the channel-boards arranged above and in front of the motors, the upper board being removable to provide accessibility to the pneumatic motors.
33. In a machine for playing pianos and the like, an angular channel board having a horizontal top portion and a vertical front portion, a series of primary valves mounted just below said channel-board, each carry-
- ing a diaphragm, a tracker board and a series of wind passages each connecting said tracker with one of said diaphragms, said diaphragms being supported in the base of the vertical portion of said channel-board and in the front of said machine, and in a single line, whereby they are rendered easily accessible, as and for the purposes described.
34. In a machine for playing pianos and the like, a series of strikers suitably supported and located in line, a series of pneumatic motors located in two or more tiers in front of said strikers whereby each motor lies in front of its own striker, primary and secondary air chambers located below said pneumatic motors in the same horizontal plane, a series of diaphragm chambers, and valve controlling diaphragms rectangular in shape arranged horizontally in the same plane and having their greatest diameters crosswise the line upon which they are arranged, each diaphragm carrying a primary valve, and each diaphragm lying in substantially the same vertical plane with one of said strikers, means for operating each diaphragm, whereby motion is communicated to the valves connected therewith and air passages provided with openings controlled by said valves whereby the motion of each diaphragm causes the operation of one of said motors and its striker as described.
35. In a machine for playing pianos and the like, a channel board having a horizontal section and a vertical section, and a tracker board projecting cornerwise from the junction of said sections of said channel board, two paper rolls, one located on each side of said tracker board and in close proximity thereto, a series of strikers arranged along the rear edge of said channel board, a series of pneumatic motors arranged upon the under side of the horizontal section of said channel board and in front of said strikers, a series of diaphragm chambers located in line upon the farther side of the vertical section of said channel board from said strikers, a series of diaphragms each diaphragm closing one side of its diaphragm chamber, a series of valves each carried by one of said diaphragms, a series of air passages each connecting said tracker board with one of said diaphragm chambers, pneumatic means connecting each of said diaphragm chambers with one of said pneumatic motors, whereby the movement of each diaphragm will cause a corresponding movement of its motor and striker.
36. In a machine for playing pianos and the like, a series of angular striking fingers, each having a horizontal portion and a vertical portion, a series of pneumatic motors located in front of said strikers, and a stop located at the lower extremity of said strik-

ers and adapted to engage with all of them, all arranged together, substantially as described, whereby there is an unobstructed space below the horizontal portions of said fingers of sufficient extent to allow said fingers to project over the key-board of the piano, and said stop to project under said key-board, for the purposes set forth.

37. In a machine for playing pianos and other musical instruments, the combination of the fingers or strikers, the pneumatic motors, a sectional air chamber, channels connecting it with the motors, air exhaust reservoirs of different powers connected with sections of said air chamber, the lesser of which exhausts automatically and the greater of which exhausts at the will of the operator, the secondary valves controlling the action of the motors, the primary valves controlling the action of the secondary valves and the air chamber of which is connected with the reservoir of higher power.

38. In a machine for playing pianos and other musical instruments, the combination of the sectional air chamber f^3 connected with the pneumatic motors, its exhaust passage g^4 , a check valve g^5 for each passage, the exhaust passage H connected with each of the sections of the air chamber and the valves H^1 , H^2 , one of which controls the connection of the passage H with one section of the air chamber and the other of which controls the connection between the passage H and the other section.

39. The combination of an exhaust chamber, two bellows of different power, passages connecting the said bellows with said exhaust chamber, means to open and close one of said passages, and pneumatically operated means to automatically open and close the other of said passages.

40. The combination of a sectional ex-

haust chamber, two bellows of different powers, passages connecting the stronger of said bellows with the said sectional exhaust 45 chamber, stop valves in said passages, passages connecting the weaker of said bellows with said sectional chamber and check valves in said passages.

41. The combination of a sectional exhaust chamber, two bellows of different power, connections between said bellows and said exhaust chamber, means for manually controlling the passages between the stronger bellows and said exhaust chamber, 55 and means for automatically controlling the passages between the weaker of said bellows and said exhaust chamber in a manner whereby a more complete connection between either section of the said exhaust 60 chamber and the said stronger bellows may interrupt the connection between the section of the exhaust chamber so connected and the weaker bellows, thus establishing a difference of pressure in the two sections of 65 said exhaust chamber.

42. In a piano player, two bellows of different power, an exhaust chamber, passages connecting said bellows with said exhaust chamber, means to open and close one of 70 said passages, pneumatically operated means to automatically open and close the other of said passages, in combination with motors, passages connecting said exhaust chamber with said motors, valves located 75 and adapted to control the pressure in said passages, a tracker board, wind passages in said tracker board, and valves adapted to be moved by change of pressure in said wind passages.
